UNITED STATES PATENT OFFICE.

CHARLES B. ALYEA, OF DOWNTON GROVE, ILLINOIS.

PNEUMATIC PUMP.

Application filed November 26, 1924. Serial No. 752,414.

My invention relates to a pneumatic pump of the intermittent operating variety and has for its primary object the provision of a pump in which compressed air is utilized as a lifting force and in which a cylinder is employed having an air inlet port and an air outlet port therein with a set of levers to which an upper and lower float are connected which are adapted to alternately open and close the said intake and outlet ports, the said floats operating independently of each other, and in which the said levers are locked by one float and released by the other float.

Another and further object of my invention is the provision of a pneumatic cylinder having a cylindrical casing which is comparatively small in diameter and which is adapted to be inserted in drilled or bored wells, as well as in open wells and the like, and in which a minimum size is required in order to insert the cylinder in the casing.

Another and further object of my invention is the provision of a pneumatic pump in which the arrangement of floats is such that the full capacity of the cylinder is utilized in operating the device.

Another and further object of my invention is the provision of a pneumatic cylinder which is simple and efficient in operation and which is not easily clogged or otherwise put out of operation by sand and the like lodging in the pump and causing leakage therein.

These and other objects of my invention will be more fully and better understood by reference to the accompanying sheet of drawings and in which:

Figure 1 is a longitudinal view partially in section and partially in elevation of my improved pump showing the valve operating levers in upper locked position;

Figure 2 is a longitudinal view partially in elevation and partially in section taken at right angles to the view of Figure 1 on line 2-2 of Figure 1; and

Figure 3 is a detail view partially in elevation and partially in section showing the locking levers in their lower locked position.

Referring now specifically to the drawings and in which like reference characters refer to like parts throughout, a cylindrical casing 10 is shown having an upper head 11 therein and secured thereto in any approved manner, the said head 11 having an air inlet port 12 controlled by a valve 13 mounted on

the upper end of a valve rod 14 which is connected by means of a link 15 at its lower end to a bell crank lever 16 by a pin 17. On the opposite side of the cylinder head 11 from the inlet port 12, is an air exhaust port 18 which is opened and closed by means of a valve 19 mounted upon a valve rod 20 which has a nipple 21 at the lower end thereof with a second rod 22 mounted in a nipple 23 over which an expansion spring 24 is mounted, the rod 22 being slidably mounted in the nipple 23 so that the valve 19 is pushed against the seat around the port 18 by the pressure of the spring 24, the nipple 23 being secured to a bell crank lever 25 by means of a pin 26. The lever 25 is pivotally mounted at its outer end upon a pin 27 mounted at one end of and extending through a pair of cross members 28 and 34 which are secured to the sides of the casing 10 at each of their ends by spot welding or the like, the bell crank 25 projecting inwardly towards the center of the cylinder 10 and has an angularly disposed portion 29 at the end thereof to which a rod 30 is secured by means of an eye 31 formed on the rod 30 with an upper float 32 mounted upon the upper end of the rod 30. The bell crank lever 16 is mounted upon a pin 33 which extends through the cross members 28 and 34 at their opposite ends from the pin 27, the crank lever extending inwardly towards the center of the casing 10 and having an angularly disposed end 35 projecting outwardly and downwardly therefrom to which a rod 36 is secured by means of an eye 37, formed in said rod 36, the said rod 36 having a sleeve 38 mounted thereon at the lower end of which a lower float 39 is secured. Connecting the levers 16 and 25 at the points where the said levers turn is a pair of links 40 and 41, the links 40 and 41 having pins 42 and 43 extending through the ends thereof and through the bell crank levers 16 and 25 respectively, the said links 40 and 41 forming a continuation in effect of the levers 16 and 25 alternately when these levers are in their upper and lower locked positions. The levers 16 and 25 with the links 40 and 41 when in their upper and lower positions respectively, form an arch or truss across the casing 10 with the pins 42 and 43 at the uppermost and lowermost points of the arch respectively. The ends 29 and 35 are turned

at an angle to the levers 25 and 16 respectively so that when the levers are pulled into their locked positions the centers of the pins 42 and 43 are outside of a line drawn from the centers of the pins 33 and 43 and 27 and 42 respectively, so that force applied to the outside of the arch has no effect thereon and does not result in any movement of the levers 16 and 25, the lines of force passing directly to the pins 27 and 33. This truss or arch is alternately formed with a long and a short side depending upon the alignment of the links 40 and 41 with the levers 16 and 25 and when force is applied to the long arm 15 alone from the inside of the truss, the truss is broken and is again formed on the opposite side of the horizontal center. The force for breaking the truss is applied to alternate sides thereof by the counterweights 32 and 39 as the water in the cylinder raises and lowers these floats. It will be noted that the angular portion 35 of the lever 16 and the member 25 are parallel with each other when the levers are in the position shown in Figure 2, and that the upper edge of the portion 35 contacts against the lower edge of the portion 25, and the same condition applies to the portion 29 and the lever 16 as shown in Figure 3, when the truss is formed 20 on the lower side of the horizontal plane referred to above.

The cylinder head 11 has a chamber 44 extending transversely therein into one side of which a pipe 45 terminates, the said pipe 35 extending downward along the outer wall of the casing 10 to the lower end thereof and has a bolt 46 positioned in the lower end of the pipe which extends through the lower cylinder head 47. At the opposite side 40 of the casing is a similar pipe 48 also terminating in the transversely extending chamber 44 in the cylinder head 11, the said pipe 48 having a bolt 49 in the lower end thereof which extends through the lower cylinder head 47, a cap 50 being provided which extends over the lower end of the cylinder 45 and which carries a projection 51 within which a valve stem 52 is seated secured to a valve 53 which holds the gravity operated 50 valve 53 in position, the valve 53 having the usual gasket 54 secured thereto and which seats upon an annular shoulder 55 formed in the head 47, the lower head 47 and cap 50 having openings therein through which 55 water passes into the casing 10.

The said outlet pipes 45 and 48 have ports 56 and 57 at their lower ends and the cylinder head 11 has an outwardly projecting portion 58 which is internally threaded and to which an outlet pipe is secured with a check valve 59 located therein to prevent the water flowing backward into the cylinder as will be more fully described hereinafter.

The operation of the device is exceedingly 65 simple in that it is placed below the water

line in an ordinary well or a bored or a drilled well, as the case may be, with a pipe which leads to any suitable source of compressed air supply secured to the head 11 at the internally threaded point 60, adjacent 70 the air inlet port 13. A similar outlet pipe line leading to the atmosphere is connected to the cylinder head 11 at 61 adjacent the air outlet port 18. Assuming that the water in the cylinder is being exhausted by air 75 under pressure being admitted thereto, the lower float 39 drops downward, the sleeve 38 sliding along the rod 36 until its weight is suspended from the end 35 of the lever 16 by means of the rod 36, the weight of the 80 float 39 being sufficient to break the long arm of the truss by pulling the lever 16 around the pin 33 and thus unlocking the levers 16 and 25 and pulling the ends of the levers 16 and 25 downward into the position 85 shown in Figure 3, thereby drawing the valve 13 downward and closing the intake port 12 and at the same time pulling the valve 19 away from its seat and opening the air exhaust port 18 which thus allows the 90 compressed air to escape from the cylinder 10. Thereupon water enters the casing 10 by lifting the valve 53 in the lower end of the cylinder 10 and the cylinder fills with 95 water, driving out the air which has been reduced to atmospheric pressure in the cylinder and as the cylinder 10 fills with water the float 39 rises, the sleeve 38 sliding along the rod 36 until the upper end of the sleeve 38 comes in contact with the eye 37 in the rod 36. This float remains in this position for the time being because its lifting force is applied to the pin 42 and the force thereby being divided against the pins 27 and 33 so that the arch formed below the horizontal 100 plane of the pins 27 and 33 remains intact until force is applied to the long arm of the arch by an upward pull of the float 32 as hereinafter described. The members 28 and 34 are curved outward so there is sufficient clearance between these members at their centers so the pins 42 and 43 can pass between these members.

The cylinder continues to fill with water and as the water rises in the cylinder the 105 float 32 exerts an upward pull on the lever 25 and thus pulling the levers out of their locked lower position and into the position shown in Figure 1, thus opening the air inlet port 12 and closing the outlet port 18, whereupon compressed air is admitted into the cylinder 10, the air forcing the water out of the cylinder 10 through the ports 56 and 57 and the outlet pipes 45 and 48 lifting the 110 check valve 59 and forcing the water out of the cylinder 10 to any place desired, depending upon the pressure of the compressed air supply to the cylinder. As the water recedes the float 32 is sustained by the levers 115 in their upwardly arched position which in 120 125 130

this position are above the horizontal plane so that the force applied to these levers in a downward direction at the center of their angle is transmitted directly to the pins 33 and 27 and the levers are thus locked in position against movement from this side. However, as the water recedes in the lower portion of the cylinder the float 39 recedes with the water, the sleeve 38 sliding down over the rod 36 until the float is near the bottom of the cylinder when it exerts its force upon the bell crank 16 pulling the levers downward into the position shown in Figure 3 and thus closing the air inlet port 12 and opening the air port 18 when the cycle of operations heretofore described is again completed. A steady flow is obtained, if desired, by using a small equalizing tank on the water line.

It will thus be understood that the bell cranks 16 and 25 after having been acted upon by the floats 32 and 39 respectively, are locked against counteraction by the said floats and that movement of the levers 16 and 25 is always accomplished by the floats acting alternately and that the levers are held in locked position until conditions change in the cylinder 10 to cause either the upper or lower float to operate depending upon whether the water is rising in the cylinder or being exhausted therefrom. The casing 10 can be made as long as may be desired and the full length thereof utilized by positioning the floats 32 and 39 adjacent the upper and lower ends thereof and with each operation the casing 10 becomes substantially filled with water and is also substantially emptied with each operation of the device. The admission of compressed air into the water, of course, causes the valve 53 to seat so that the water is forced out through the ports 56 and 57.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A pump comprising a casing having air inlet and outlet ports and water inlet and outlet openings, valves controlling the air inlet and outlet ports and water openings, a pair of pivotally mounted levers adapted to open and close the air valves, the said levers co-acting to form arches above and below the pivotal mountings, connections between said levers and the air valves and means operated by the water whereby a pulling force is exerted on said levers when in arched position thereby opening and closing the air inlet and outlet ports.

2. A pump comprising in combination a casing having air inlet and outlet ports and water inlet and outlet openings, valves controlling said air ports and water passages, a pair of levers, pivotal mountings for said levers intermediate the ends of said casing, connecting rods connecting said levers and the valves controlling the said air inlet and outlet ports, upper and lower floats connected to said levers and controlled by the rise and fall of the water in said casing for actuating said levers, and a link connecting the said levers.

3. A pump comprising in combination a casing having air inlet and outlet ports and water inlet and outlet openings, valves controlling said air ports and water passages, a pair of levers, pivotal mountings for said levers intermediate the ends of said casing, connecting rods connecting said levers and the valves controlling the said air inlet and outlet ports, the said levers having angularly disposed ends; a link connecting the said levers, and upper and lower floats connected to said levers controlled by the rise and fall of the water in the said casing for actuating the said levers.

4. A pump comprising in combination a casing having air inlet and outlet ports and water inlet and outlet openings, valves controlling said air ports and water passages, a pair of levers, pivotal mountings for said levers intermediate the ends of said casing, connecting rods connecting said levers and the valves controlling the said air inlet and outlet ports, connecting members between the said levers whereby the said levers form arches across said casing in upper and lower positions and an upper float adapted to actuate said levers in one direction as the water is rising in said cylinder and a lower float adapted to operate the said levers as the water is forced out of said casing.

5. A pump comprising in combination a casing having air inlet and outlet ports and water inlet and outlet openings, valves controlling said air ports and water passages, a pair of levers, pivotal mountings for said levers intermediate the ends of said casing, connecting rods connecting said levers and the valves controlling the said air inlet and outlet ports, connecting members between the said levers whereby the said levers form arches across said casing in upper and lower positions, and an upper float adapted to 120 actuate said levers in one direction as the water is rising in said cylinder and a lower float adapted to operate the said levers as the water is forced out of said casing, the said lower float being slidably mounted upon the end of one of said levers.

6. A pump comprising in combination a casing having air inlet and outlet ports and water inlet and outlet openings, valves controlling said air ports and water passages,

a pair of levers, pivotal mountings for said levers intermediate the ends of said casing, connecting rods connecting said levers and the valves controlling the said air inlet and outlet ports, connecting members between the said levers whereby the said levers form arches across said casing in upper and lower positions, an upper float adapted to actuate said levers in one direction as the water is rising in said cylinder and a lower float adapted to operate the said levers as the water is forced out of said casing, a pair of bell crank levers having angularly disposed ends, the said ends extending parallel to the body portion of each of said levers when in locked relation, and upper and lower floats operated by the rise and fall of the water in said casing and adapted to pull the said levers into and out of locked relation with each other.

7. A pump comprising in combination a casing having air inlet and outlet ports and water inlet and outlet openings therein, a pair of pivotally mounted levers in said casing, means connecting said levers whereby the said levers are formed in upper and lower arched positions in said casing, floats actuated by the rise and fall of the water in said casing, means connecting the said floats and the said levers, and operating connections between the said levers and the valves controlling the air ports.

8. A pump comprising in combination a casing having air inlet and outlet ports and water inlet and outlet openings therein, a pair of pivotally mounted levers in said casing, means connecting said levers whereby the said levers are formed in upper and lower arched positions in said casing, floats actuated by the rise and fall of the water in said casing, connecting means for said floats and said levers and operating connections between the said levers and the valves controlling the air ports, each of said levers having angularly disposed ends adapted to lie against the edge of the co-operating lever when the levers are in arched positions.

9. A pump comprising in combination, a casing having air inlet and outlet ports and water inlet and outlet openings, valves controlling the air inlet and outlet ports and water openings, a pair of co-acting levers pivotally mounted in said casing, connections between the said levers and the valves controlling the air inlet and outlet ports, means connecting the said levers, the said levers and connecting means forming arches above and below the pivotal centers of the levers, and means operated by the movement of the water in the casing whereby a pulling force is exerted on said levers when in arched position thereby breaking the arch on one side of said center and reforming it on the other side of said center, and opening and closing the air inlet and outlet ports.

10. A pump comprising in combination, a casing having air inlet and outlet ports, water inlet and outlet openings, valves controlling the air inlet and outlet ports and water openings, a pair of co-acting levers pivotally mounted in said casing, connections between the said levers and the said valves controlling the air inlet and outlet ports, means connecting the said levers, floats in the said casing, and means connecting the said floats and the said levers, the said floats co-acting to force the said levers and connecting means into arched positions on each side of the pivotal mountings of the said levers.

11. A pump comprising in combination, a casing having air inlet and outlet ports and water inlet and outlet openings, valves controlling the air inlet and outlet ports, co-acting levers pivotally mounted in said casing, a pivotally mounted member connecting the said levers, means connecting the said levers and the valves controlling the air inlet and outlet ports, an upper float connected to one of said levers, and a lower float connected to the other lever.

12. A pump comprising in combination, a casing having air inlet and outlet ports and water inlet and outlet openings, valves controlling the air inlet and outlet ports, co-acting levers pivotally mounted in said casing, a pivotally mounted member connecting the said levers, means connecting the said levers and the valves controlling the air inlet and outlet ports, an upper float connected to one of said levers, and a lower float connected to the other lever, the rise and fall of the water in said casing causing the floats to form the said levers and connecting member into arched positions above and below the pivotal centers of the levers, the connecting member being in alignment with one of said levers in one position of the arched form of the levers and with the other lever in the other arched position.

13. A pump comprising in combination, a casing having air inlet and outlet ports and water inlet and outlet openings, valves controlling the air inlet and outlet ports, co-acting levers pivotally mounted in said casing, a pivotally mounted member connecting the said levers, means connecting the said levers and the valves controlling the air inlet and outlet ports, an upper float connected to one of said levers, and a lower float connected to the other lever, the said levers and connecting member being formed in arched position in said casing by the floats and adapted to sustain the weight of one of the floats on the outside of the arch.

14. A pump comprising in combination, a casing having air inlet and outlet ports and water inlet and outlet openings, valves controlling the air inlet and outlet ports, co-acting levers pivotally mounted in said cas-

ing, a pivotally mounted member connecting the said levers, means connecting the said levers and the valves controlling the air inlet and outlet ports, an upper float connected to one of said levers, and a lower float connected to the other lever, the said levers and connecting member being formed in arched positions by said floats, the said connecting member forming an extension with one of said levers in one arched position and an extension with the other of said levers in the other arched position. 10

CHARLES B. ALYEA.
